UNITED STATES PATENT OFFICE

EDMUND KOCH, OF ESSEN, GERMANY

RESPIRATOR

Application filed October 7, 1930, Serial No. 487,051, and in Germany April 10, 1929.

In the use of closed respiration apparatuses, accidents having serious consequences are from time to time caused by the fact that on fitting on the apparatus, which mostly takes 5 place under a certain amount of excitement, the wearer forgets to open the valve of the oxygen flask. In breathing with the apparatus, this oversight can easily remain unnoticed. The capacity of the air path of such 10 a respiration apparatus amounts to about 8-10 litres. For respiration, however, only the variable contents of the respiration sack come into consideration. When the apparatus with the oxygen flask unopened is used 15 by the wearer thereof, after a short time, not exceeding approximately about two minutes, nitrogen narcosis takes place. If the oversight is then noticed, unconsciousness has, under certain circumstances, progressed 20 to such an extent that the wearer of the apparatus is no longer capable of opening the valve of the oxygen flask.

The same danger is present with respiration apparatuses with the chemical production 25 of oxygen. Several minutes elapse before the bursting of the chemical cartridge, that is, before there is sufficient chemical oxygen production. In order to provide the wearer until such time with sufficient oxygen, a small auxiliary flask of oxygen is fitted 30 in the apparatus, the contents of which suffice until the bursting of the cartridge. Capsules or flasks with a chemical starting medium, as for example with a filling of carbonic acid, are provided which on opening 35 effect an immediate production of oxygen by the chemical combination of the carbonic acid with the oxygen producing chemical of the cartridge. There are also chemical cartridges for the operation of which a movement by the wearer of the apparatus is necessary. If the wearer forgets to start the action 40 of such cartridges or of the auxiliary or starting medium, this is not at first noticeable in breathing. Difficulty in breathing 45 does not take place, but only the remainder of the oxygen contained in the apparatus is used, so that the wearer of the apparatus is 50 subject to the danger of nitrogen narcosis until the bursting of the chemical cartridge.

To avoid this defect, with the closed respiration apparatus with oxygen storage container according to the invention, a blocking means for the respiration circuit is provided which is so controlled either by the pressure 55 of the oxygen contained in the storage container, or by a member effecting the opening of the blocking valve of the oxygen container, that the respiration circuit is open with opened oxygen container and is closed with 60 closed oxygen container. For this purpose, for example the blocking means for the respiration circuit can be connected with a tube spring connected on the oxygen container behind its closing valve, which spring 65 straightens owing to the pressure of the entering oxygen and thus moves the blocking means into the open position. With closed respiration apparatuses with chemical cartridges producing oxygen, the blocking 70 means provided for the respiration circuit is connected with a member moved on the actuation of the auxiliary or starter means for the chemical cartridges, for example with the cut off valve of an oxygen auxiliary flask, in 75 such manner positively that on the operation of the auxiliary or starter means, the respiration circuit opens.

Owing to this cut-off means, on putting on the apparatus the respiration circuit is temporarily blocked. Impossibility of breathing compels the wearer of the apparatus to at once open the oxygen flask or start the chemical cartridge developing oxygen, the auxiliary or the starter medium whereby 85 there then takes place simultaneously the opening of the respiration circuit.

The invention is shown on the annexed drawings in several examples of execution.

Figure 1 is a diagrammatic view partly in 90 section of an embodiment of an oxygen respiration apparatus with pneumatically opening cut-off valve in the respiration circuit.

Figure 2 is a section of this cut-off valve 95 on a larger scale,

Figure 3 is a section of another embodiment of the cut-off valve opening pneumatically, and

Figure 4 shows diagrammatically and partially in section the construction of a part of 100

the oxygen respiration apparatus with mechanically actuated cut-off valve.

The inhaling pipe *b* and the exhaling pipe *c* open into the face mask *a*. From the exhaling pipe, the exhaled air flows through the air purifying cartridge *d* partly into the respiration sack *e*, and partly into the channel leading to the spray nozzle *f* and to the inhaling pipe *b*. The spray nozzle *f* connected to the oxygen flask *g* draws the respiration air from behind the nozzle and blows it mixed with fresh oxygen, into the pipe *b*.

In order to make breathing with the oxygen flask closed impossible, the cut-off means *h* is provided for the inhaling pipe, and this is so related and arranged with reference to the oxygen flask that on the opening of the oxygen flask it also opens the respiration circuit, while such passage is blocked when the oxygen flask is closed.

This dependence of the cut-off valve *h* on the opening and closing of the oxygen or starting medium flask can be attained either by the pressure of the oxygen or starter medium, that is, by pneumatic means, or by mechanical means, as for example by a positive connection of the cut-off means *h* with the cut-off valve of the oxygen flask. The method of obtaining this interdependence can be carried out in numerous ways. With the respiration apparatuses with chemicals giving up oxygen, there can be used in addition to, or in place of, an oxygen auxiliary flask, any other starting means, when by the actuation of the starter apparatus, the cut-off valve in the respiration circuit of the apparatus is moved by a corresponding device.

Several examples of construction are shown in the drawings. According to Figures 1 and 2, the cut-off valve *h* is actuated by a tube spring *i*. These tube springs, known for example, with pressure gauges, consist of a small thin walled bent steel tube closed at one end. They have the property of extending according to the strength of the pneumatic or hydraulic pressure existing therein, and on the removal of the pressure of again assuming their original bent shape owing to their spring action. The valve flap *h* is shown attached to the closed end of this tube spring *i*. By means of its spring action, the tube spring *i* when no pressure exists, holds the cut-off means *h* in a position to close the breathing pipe. The open end of the tube spring *i* is connected by the pipe *k* with the oxygen flask *g*. On the opening of this flask, the pressure of the oxygen is transmitted at once through the pipe *k* on to the tube spring, causing the latter to assume the position shown in broken lines (Figure 2), lift the valve *h*, thus opening the respiration circuit.

In Figure 3 is shown another example for the pneumatic actuation of the cut-off valve *h*. The pipe connected with the oxygen flask

g is connected with a cylinder *l* in which is carried a piston under spring pressure which by means of a lever rod keeps the valve *h* closed as long as there is no pressure in the cylinder *l*. By means of the pressure of the oxygen entering the cylinder through the pipe *k*, the piston is raised and the valve *h* opened. If the pressure of the oxygen ceases, the piston returns under the action of the spring to its initial position and closes the cut-off means *h*.

The pneumatic actuation of the cut-off valve in the examples described necessitates no loss of oxygen, since no oxygen escapes, and only its pressure is utilized. The dependence of the pneumatically actuated cut-off means on the opening and closing of the oxygen flask may also be carried out in the reverse manner by the means serving for the closing of the valve being in a continuous open connection with the oxygen flask, and this connection being broken by the opening of the flask.

As a hand wheel or lever movement is necessary for the opening and closing of the oxygen flask, the actuation of the cut-off means *h* may also be made mechanically dependent on this movement. In Figure 4, an example of this is shown. On the spindle of the cut-off valve of the flask *g* is fitted a small pinion *p* which follows the rotation of the hand wheel *m*. The pinion *p* is in engagement with a pinion *o* which is carried on a spindle carried by plates and clips on the fittings of the flask *g*. The spindle *n* has adjacent one end suitable screw threads engaging the body of the valve *h*, so that on rotation of the spindle *n* the valve *h* is raised or lowered and thus the valve is opened or closed. On the rotation of the hand wheel *m* of the flask *g* the spindle *n* is also rotated by the pinions, so that the valve *h* opens when the flask is opened.

For this mechanical dependence of the cut-off device *h* on the movement of the valve of the flask *g*, many means of transmission are also possible.

With closed respiration apparatuses with oxygen developing chemical cartridges, the actuation of the auxiliary or starter means, as for example the cut-off valve of an oxygen auxiliary flask, may be brought in the same or a similar manner as in the embodiments described, into such dependence on the cut-off body of the valve provided for the respiration circuit, that on the operation of the auxiliary or starting means, the respiration circuit is opened.

The cut-off device can be arranged at any desired position of the respiration circuit, if necessary with a corresponding arrangement of the respiration sack *e*, in this also. The connection of the cut-off device with the inhaling pipe would be most advantageous. The position at which the cut-off device is

fitted is dependent on the position of the flask valve or of the starter means.

What I claim and desire to secure by Letters Patent of the United States is:—

- 5 1. In a closed circuit respiration apparatus, the combination with an oxygen storage container, of a valve normally interrupting flow through the respiration circuit of the apparatus, and means whereby said valve will 10 be automatically moved to open position when the oxygen storage container is placed in communication with the respiration circuit and closed when communication between said circuit and oxygen container is cut off.
- 15 2. In a closed circuit respiration apparatus, the combination with an oxygen storage container, of a valve normally interrupting flow through the respiration circuit of the apparatus, and means actuated by pressure 20 from the oxygen container for automatically moving said valve to open position when said container is placed in communication with the respiration circuit of the apparatus.
- 25 3. In a closed circuit respiration apparatus, the combination with an oxygen storage container, of a valve normally interrupting flow through the respiration circuit of the apparatus, a second valve controlling communication between the oxygen container and the 30 respiration circuit of the apparatus, and a mechanical connection between said valves whereby they will be both simultaneously moved to open or closed position.
- 35 4. In a closed circuit respiration apparatus, the combination with an oxygen storage container, of a valve normally interrupting flow through the respiration circuit of the apparatus, a conduit communicating with said oxygen storage container, and a tube spring 40 having one end thereof in communication with said conduit and the other end connected to said valve, whereby pressure from said oxygen container will automatically move said valve to open position when said container is placed in communication with the 45 respiration circuit of the apparatus.
- 50 5. In a closed circuit respiration apparatus, the combination with an oxygen storage container, of a valve normally interrupting flow through the respiration circuit of the apparatus, a conduit communicating with said oxygen storage container, a cylinder communicating with said conduit, a piston movable in said cylinder, and a mechanical connection between said piston and valve, whereby pressure from said oxygen container will 55 automatically move said valve to open position when said container is placed in communication with the respiration circuit of the apparatus.

EDMUND KOCH.
